UNITED STATES PATENT OFFICE.

FRANK CHASE, OF WATERVILLE, MAINE.

PRESS.

SPECIFICATION forming part of Letters Patent No. 558,011, dated April 7, 1896.

Application filed September 12, 1895. Serial No. 562,272. (No model.)

To all whom it may concern:

Be it known that I, FRANK CHASE, a citizen of the United States, residing at Waterville, in the county of Kennebec and State of Maine, 5 have invented a new and useful Improvement in Presses, of which the following is a full, clear, and exact description, reference being had to the accompanying drawings, forming a part of this specification, in explaining its 10 nature.

The invention relates to an improvement in presses by which the bed or movable head is provided with a relatively large throw in relation to the stationary head or tool of the 15 press by means of a treadle having a relatively small motion and intermediate connecting devices comprising a primary lever connected with the treadle at one end and with the head at the other end pivoted to a 20 secondary lever and adapted to move the spindle and the bed during the greater part of its movement, and the said secondary lever being adapted to be brought into operation by the action of the first lever in giving 25 the bed or press a powerful closing or finishing movement.

The invention is represented as applied to a machine for pinking or cutting serrations in the toe or heel section of an upper preparatory to lasting them in.

In the drawings, Figure 1 is a view in front elevation of a press having the features of my invention. Fig. 2 is a view in horizontal section upon the dotted line $x-x$ of Fig. 1 and 35 in plan of the parts below said line. Fig. 3 is a view in vertical central section of the press from front to rear; and Fig. 4 is a view principally in side elevation thereof, a part of the frame being broken out to show the 40 position of the levers at the end of the pressing movement.

A is the frame of the machine. It has the base a , of any desired width, adapted to be mounted upon a bench and to be bolted thereto, and the overhanging head B, having ears b b' , the under surface of which is plain or perfectly flat and acts as a stationary head against which the upper edge c of the pink-

ing-knife D is held by the clamping-studs c' and c'' , the studs having their lower ends 50 slotted to receive the ends of the pinking-knife, the ends entering the slots and being secured to the studs by screws, and the studs extending through slots c^3 in the ears, by which they are adapted to be moved in or out 55 in relation to each other to vary the curve of the pinking-knife, and the studs being fastened in any desired position to the ears by means of the clamping-nuts c^4 . The pinking-knife has at its center a hole c^5 , into which 60 extends a pin c^6 , fast in the press-frame, (see Fig. 3,) the said pin serving to support the back of the pinking-knife and to center it, it being understood that the knife is made of flat steel bent to a corrugated or zigzag form, 65 (see Fig. 2,) the arc of which may be readily changed by moving its ends inward or outward and the lower edge of which is sharpened. The knife, of course, is stationary, as would be any other part or tool secured to 70 the stationary head.

D' is the movable bed or head of the press. It carries a working face d , of soft metal or any suitable material. It is attached to the upper end of the stud or spindle d' , and it 75 has in its back surface a recess d^2 , which receives an extension d^3 from the press-frame, whereby it is guided and prevented from turning in its vertical movements. The stud or spindle d' is supported in bearings formed in 80 the bracket d^4 and in the press-frame at d^5 , and below the bracket, between it and a collar d^6 on the stud or spindle, is a compression-spring d^7 , which is compressed by the upward movement of the spindle, and which 85 serves to move downward the spindle and movable head or bed upon the completion of the work and the removal of the cam-section of one of the actuating-levers from beneath the end of the spindle. The spindle has upward movement imparted to it, first, by means of the lever E, pivoted at e to the lever E'. One end of this lever extends beneath the pin d^8 , upon which the roll d^9 at the lower end of the spindle is carried. The other end 90 of the lever is connected by a link or rod e'

with the operating-treadle E². The lever E' is pivoted to the press-frame at e³ below the center of the spindle d', and its short end e³ is practically at a right angle to its arm e⁴, and its upper surface e⁵ is tangential to a circle struck from the pivotal point of the lever and forms a cam.

At the end of the long arm e⁴ of the lever E' is a cross-piece or ear e⁶, against which the lever E is drawn at the end of its head-lifting action. These ears e⁶ are used when the lever E is formed as a sort of gate—that is, of two side bars connected with each other by cross-pins, so that they straddle at their ends the roll d⁹ and also the ear on the long arm of the lever E' and receive the upper end of the link e' by a connecting-rod.

The operation of the levers is as follows: The movable head or bed being depressed 20 the levers have the position represented in Fig. 3—that is, the lower end of the primary lever E is beneath the roll-stud of the spindle in a position to lift the spindle. The secondary lever E' has its cam end moved out of line 25 with the spindle, so that the end of the spindle may close down by it, and its long arm is inclined upwardly. Upon the application of downward pressure or movement to the outer end of the lever E the spindle and press head 30 or bed are moved rapidly upward, this movement being a relatively rapid one because of the leverage of the lever. When it has very nearly been moved to the point where greater pressure is required for completing the operation 35 of the press, the spindle and its roll have so far lifted that by a farther downward movement of the lever E and treadle the entire pressure is brought to bear upon the lever E', and its cam end then comes in contact 40 with the lower part of the roll and is moved under it, the leverage having been changed from that of the lever E, fulcrumed at e', to that of the levers E and E', fulcrumed at e², or very much increased. As, however, this 45 largely increased pressure is necessary for only a small part of the throw of the spindle and movable head or bed, this change in leverage does not require that the treadle E² be provided with much additional throw. It 50 will be seen that there is thus provided means by which, upon a relatively small movement of the treadle E², the movable head is given quite a large range of movement and without in any way diminishing the degree of power 55 needed at the last end of the stroke, but on the contrary increasing it.

A press having a relatively large throw or movement of the head with increased pressure at the end is very necessary for many 60 kinds of work and especially for serrating or pinking toe and heel edges of boot and shoe uppers. A spring F is attached to the frame and to one of levers E or E' to lift them and the treadle after the pressing operation is completed. It will be seen that the levers are 65

held in a chamber in the lower part of the press-frame.

Having thus fully described my invention, I claim and desire to secure by Letters Patent of the United States—

1. In a press in combination with a stationary head or bed a head or bed movable toward the stationary head or bed by an actuating mechanism comprising two levers, E, E', the lever E being an accelerating-lever and pivoted to the lever E', and the lever E' having a compression-cam adapted to act upon the movable head or bed after the action of the accelerating-lever, as and for the purposes described. 75

2. In a machine of the character specified the combination of the movable head or bed D', its spindle d', the spring d² and the levers E, E' and treadle E² connected with the end of the lever E, the lever E being pivoted to the lever E' and engaging the spindle d' for the principal part of its throw, and the lever E' having a compression-cam e⁵ which engages the spindle at the completion of the actuating movement of the lever E, the said levers being 85 operated successively by a single downward movement of the treadle, as and for the purposes described. 90

3. The combination in a machine of the character specified of the frame A having an overhanging integral head B, and integral ears b, b' extending from each side thereof, the under surface of which head and ears forms the stationary bed of the machine, a curved serratting or pinking knife attached to the said 95 head by means of a pin c⁵ which enters the hole c⁶ therein and the clamping-studs c' c² to which the ends of the knife are secured and means for adjusting the curve of said knife comprising slots c³ in the said ears b, b' in 105 which the said clamping-studs are laterally adjustable, in combination with a head or work-support movable toward and from said knife. 100

4. In a machine of the character specified 110 the combination of the movable head or work-support D', the treadle, and intermediate connecting devices comprising two levers one of which is pivoted to operate the work-support relatively rapid for the greater part of its 115 throw, and the other of which is pivoted and shaped to apply relatively slow but more powerful movement to the head at the end of its throw substantially as described.

5. The combination of a machine of the 120 character specified of the pressure-head D', its spindle d', the spring d², the spindle-roll d⁹, the lever E', pivoted at e³ and having the cam e⁵ and the long arm e⁴, the ear e upon said long arm, the lever E pivoted to said ear 125 and having one end in engagement with the spindle e' during a portion of its throw, and adapted at its other end to come in contact with the end of the lever E' and to increase the leverage thereof during the operation of 130

its cam upon the spindle and means for moving the said lever E in both directions as and for the purposes described.

6. The combination of a machine of the character specified of the pressure-head, a lever for lifting it a portion of its throw and sufficiently to permit of the introduction beneath the head of the actuating part of a second com-

pressing-lever and said second compressing-lever and means for successively operating 10 them as and for the purposes described.

FRANK CHASE.
